DESIGN FOR A LIGHTING FIXTURE

Leon J. Segil, Chicago, Ill.

Application December 6, 1939, Serial No. 88,724

Term of patent 3½ years

To all whom it may concern:

Be it known that I, Leon J. Segil, a citizen of the United States, residing at Chicago, in the county of Cook and State of Illinois, have invented a new, original, and ornamental Design for a Lighting Fixture, of which the following is a specification, reference being had to the accompanying drawing, forming part thereof.

Fig. 1 is a perspective view of a lighting fixture showing my new design.

Fig. 2 is an end elevation of same.

I claim:

The ornamental design for a lighting fixture, as shown.

LEON J. SEGIL.
